UNITED STATES PATENT OFFICE.

HARRY STILLSON HART, OF CHICAGO, ILLINOIS, ASSIGNOR TO THE ROGER BALLAST CAR COMPANY, OF CHICAGO, ILLINOIS, A CORPORATION OF ILLINOIS.

METALLIC CAR.

SPECIFICATION forming part of Letters Patent No. 700,767, dated May 27, 1902.

Application filed July 3, 1899. Serial No. 722,624. (No model.)

To all whom it may concern:

Be it known that I, HARRY STILLSON HART, a citizen of the United States, residing at Chicago, in the county of Cook and State of Illinois, have invented certain new and useful Improvements in Metallic Cars, of which the following is a specification.

My invention relates to that class of cars which are formed of ordinary commercial iron or steel, and has special relation to that class of cars known as "ballast-cars," all of which will more fully hereinafter appear.

The principal object of the invention is to provide a freight-car, preferably of the well-known ballast-car type, with side plate-girders resting at each end upon a single self-contained or combined end sill and bolster, which side girders support the entire car-body and dispense with the usual side, center, and cross 20 sills, as will be more fully hereinafter set forth.

A further object of my invention is to provide a simple, economical, and efficient metallic ballast-car with two transverse members which take the place of the end sills and body-bolster and by which the car is supported and the shocks incident to use transmitted throughout the entire car.

Further objects of the invention will appear from the following description and an examination of the drawings.

The invention consists in the features, combinations, and details of construction herein-after described and claimed.

In the accompanying drawings, Figure 1 is a side elevation of a portion of a car constructed in accordance with my improvements; Fig. 2, a plan view of the same; Fig. 3, a longitudinal sectional elevation taken on line 3 of Fig. 2; Fig. 4, a plan sectional view taken on line 4 of Fig. 6 looking in the direction of the arrow; Fig. 5, an end view of the car, and Fig. 6 a transverse sectional elevation taken on line 6 of Fig. 3.

In illustrating and describing my invention I will only illustrate and describe that which I consider to be new, taken in connection with so much as is old as will properly disclose the invention and enable those skilled in the art to practice the same, leaving out

of consideration other and well-known parts, which if described here would only tend to prolixity, confusion, and ambiguity. I have also preferred to illustrate and describe my improvements in connection with what is known as a "ballast-car" for the reason that most of my new features are particularly applicable to this style of car; but it will be understood that some of these features are applicable, with slight mechanical changes, to other kinds of cars—such as gondola, flat, and even box cars—and I do not desire to be understood as limiting myself entirely to the particular type of car illustrated herein.

In the art to which this invention relates it is well known that all or nearly all railway-cars in common use are provided with what are termed end, center, sub, intermediate, and side sills and body-bolsters, which act to support the weight of the parts and load and to receive and distribute the shocks incident to usage. These parts I dispense with and supply novel elements to take their place, and it will be seen from the following description and drawings that these novel elements, as well as the entire structure of the car, are composed of ordinary commercial iron or steel, such as angle and sheet iron, so that when the car is injured and needs repair all that is necessary is to purchase ordinary commercial iron at the nearest depot, which will enable the car to be repaired economically and readily at any point of its run.

In constructing my improved car I use what I prefer to term a "combined end sill and body-bolster" A, one of which is located transversely at or near each end of the car and by which the load is sustained upon the ordinary truck-bolster, not shown or described herein. This combined end sill and body-bolster is composed of angle-irons a, which extend outwardly in a horizontal plane and act as flanges and to which are secured sheet-metal pieces a', that form the vertical members and connect the angle-irons together and also take the place of a web. An examination of Fig. 3 will show that these web portions are placed parallel to each other and on the inside, extending vertically, and that the angle-irons act as flanges, extending outwardly. In Fig. 4 it will be

seen that the web portions are separated considerably, so as to leave a space a^3 at or near the central part, but gradually approaching each other at or near the end portions, where 5 they are secured together and to a vertical plate a^3 , which is grasped between them. In Fig. 5 it will be seen that these combined end sills and body-bolsters are cambered on their lower surfaces, as at a^4 .

10 To provide the body of the car and sustain the weight thereof, two side plate-girders B are provided and are formed of angle-irons b at the lower part and b' at or near the upper part, between and to which the plate portions 15 b^2 are secured. Each end of these side plate-girders is secured to the combined end sill and body-bolster and vertical plate by means of rivets b^3 , as shown particularly in Figs. 4 and 5, upon which they rest and by which 20 they are supported. It will be noticed from an inspection of Fig. 1 that at or near the end portion and at their upper side these side plate-girders are cut away at an angle from the upper part toward the end, as at b^4 , which 25 in a measure resembles or follows the lines of a parabola, and thus provides maximum strength with the least amount of metal and an approximately equal fiber stress through the total length of the girder.

30 As above described, I prefer to use the side plate-girders B, which are formed as shown and which in the usual structures will support all the load that it is necessary to carry. It is desirable, however, at times and under 35 what might be termed "unusual" conditions to carry heavy loads of ballast, and I therefore reinforce these girders by using intermediate girders and connecting the same together, so as to form what may be termed a 40 "box" girder at each side of the longitudinal center of the car, but which would only be necessary in connection with cars intended to carry heavy ballast or weights and unnecessary in other types, such as gondola or 45 coal cars. It is desirable in order to provide for unusually heavy loads to make these side girders as strong as possible, so that the shocks and strains incident to use can be fully absorbed without injuring the car, and 50 thus satisfactorily dispense with the side and intermediate sills. To accomplish this result, I provide intermediate plate-girders formed of angle-irons C, which are arranged lengthwise of the car and secured, by means 55 of rivets and angles at each end, to the combined end sill and body-bolster, and plates C', which are riveted thereto and which extend in a vertical plane and are arranged longitudinally with the car and parallel with 60 and between the side plate-girders. These last-named girders form, with the side girders and the hopper-bottom and floor portions D and D' (which are arranged at an angle, as will be more fully hereinafter explained) 65 and diagonal lattice-bracing L, a box-girder at each side of the car and which are sus-

tained at their end portions on the combined sills and bolsters.

To sustain the floor of the car, or, in other words, the hopper-bottoms D and D' and the 70 inclined ends D² thereof, the posts E are provided and secured to the side plate-girders, extending upwardly in vertical planes. I have only shown five of these posts in the drawings; but it will also be understood that 75 I only show one-half of one side elevation of the car. These vertical posts primarily act as stiffeners for the side plate-girders and at their upper ends have secured to them the plates d and d', which extend longitudinally 80 of the car and connect with end pieces or angle-irons d². These parts d and d' practically form a portion of the side of the hopper and are secured to the side plate-girders, as well as to the vertical posts. 85

The inclined bottoms extend downwardly and inwardly toward the longitudinal center of the car, where they are provided with swinging doors G and G', that meet at the longitudinal apex of the hopper-bottom. 90 These doors are opened and closed by means of the chains g, which run across idlers g' and are connected to a rock-shaft g². The rock-shaft is provided with a ratchet g³, which is operated by means of the lever-handle g⁴ and 95 held against rotation in one direction by means of the pawl g⁵. The closing of the door is obtained by vibratory movement of the handle well known in winches and like mechanisms, while the opening is permitted by raising the 100 handle and holding the pawl out of action, thus permitting the doors to be opened by their own weight and load. These chains, which serve to open and close the doors of the hopper-bottom, are inclosed in a housing formed 105 by means of the plates H and H', as shown particularly in Fig. 3, and which are riveted to the hopper-bottom, as shown in such figure, and act not only as housings, but also as tie-rods for the hopper-bottom. 110

It is desirable to provide means by which the shocks and strains incident to the usage of the car may be distributed entirely throughout the material forming the car proper, thus minimizing the danger of destroying or injuring the car by unusual shocks or strains. In order to accomplish this result, I provide draft members I and I', which are formed of channel-beams and take the place of the draft-timbers in ordinary cars and which are 115 secured to the combined end sills and body-bolsters and extend outwardly and longitudinally therefrom and to which the ordinary draft-rigging may be secured. These draft members are braced against vertical strains 120 and by means of the braces I² and I³, which are formed of the plates i and angles i' and i'', as shown particularly in Fig. 3, and extend upwardly and backwardly from the draft members to the inclined end of the hopper-bottom, to which they are also secured by 125 means of tie-angles i³, which extend across 130

and tie the intermediate plate-girders together, and thus distribute the strains to such part. These draft elements are also braced against horizontal strain by means of the 5 plates i^4 and i^5 , which are shown particularly in Fig. 2, and are secured to the draft elements and the combined end sill and body-bolster.

To assist the combined sill and bolster in 10 carrying the load, I provide a truss-bar K, which is riveted at or near each end to the vertical plates a^3 and passed over struts K'. By this means it will be seen that the load, as 15 well as the weight of the car, is entirely carried on these combined end sills and body-bolsters, which are strong enough to resist the entire stress and strains. It will also be seen that the securing of the combined end sills and body-bolsters to the side and intermediate 20 plate-girders, which form the box-girders in combination with the lattice-work L, (shown in Fig. 4,) distributes the shocks due to the buffing and hauling of the cars throughout the entire structure.

25 End platforms are provided, as usual in such cars, and are formed of plates of sheet metal M, resting on the draft members and secured to the angle-irons m and which are further provided with side plates m' . These side angle-irons and plates are also secured to the 30 bottom of the side plate-girders and passed outside of the ends of the combined end sill and body-bolster, to the end of which they are also secured. End posts P are provided, 35 which are secured to the upright members for the draft-bracing by means of rivets and to the angle-irons running across the end of the hopper-bottom and which are used as stiffeners for such portions of the car.

40 I claim—

1. In a car of the class described, the combination of an open unobstructed body-supporting frame, composed of transverse bolsters at or near the ends, and side plate-girders 45 rigidly connected to and resting on the top of said bolsters, substantially as described.

2. In a car of the class described, the combination with a body, of supporting-frame composed of transverse bolsters at or near the ends of the body, and side plate-girders connected rigidly to and resting on the top of said bolsters, said body being entirely supported from said bolsters and side girders, 55 substantially as described.

3. In a car of the class described, the combination of a combined end sill and body-bolster arranged transversely of the car at or near each end thereof, side plate-girders supported at or near their ends by and rigidly connected to the top of the combined end sill and bolster; and a bottom portion supported by the side girders, substantially as described.

4. In a car of the class described, the combination of a combined end sill and body-bolster arranged transversely of and at or near each end of the car, a hopper portion, side

plate-girders supported at their ends upon the combined sills and bolsters and supporting the hopper, and intermediate longitudinal plate-girders supported at their ends upon the combined sills and bolsters to assist in supporting the hopper, substantially as described.

5. In a car of the class described, the combination of a combined end sill and body-bolster arranged transversely of and at or near each end of the car, a hopper portion and two box-girders supported at their ends upon the combined sills and bolsters and formed of two side plate-girders, two intermediate plate-girders, means for securing them—the side and intermediate girders—together at or near their lower portions and supporting the hopper and a portion of the sloping side 85 or bottom of the hopper, substantially as described.

6. In a car of the class described, the combination of a car-floor or bottom portion, side plate-girders supporting the same, a combined end sill and body-bolster arranged transversely of the car in position to be supported by the truck and secured to and below the ends of the side plate-girders to support the same and transmit the buffing strains to 95 such girders, and means for transversely bracing the bolster, substantially as described.

7. In a car of the class described, the combination of a car-floor or bottom portion, two side plate-girders supporting the same, a combined end sill and body-bolster arranged transversely of and secured to and below the ends of the side plate-girders to support the same and transmit the buffing strains to such girders, and a longitudinal truss member secured to each end of such combined sill and bolster to assist them in carrying the loads, 100 substantially as described.

8. In a car of the class described, the combination of a car-floor or bottom portion, two side plate-girders supporting the same, a combined end sill and body-bolster arranged transversely of and secured to the ends of the side plate-girders to support the weight thereof and transmit the buffing strains to such 115 girders, draft-rigging-supporting members secured to and extending out endwise from the combined sills and bolsters, and means for assisting such draft members in resisting side-wise and vertical strains, substantially as described.

9. In a car of the class described, the combination with a body portion of supporting side plate-girders, having their upper edges bent to fit the adjacent portions of the body, and connecting members at the ends between the girders.

10. In a car of the class described, a combined end sill and body-bolster formed of two longitudinal members separated at their central portion and brought together at their ends, a metal plate secured between the longitudinal members at each end and extending upwardly therefrom, a truss member with

its ends secured to the vertical plates, and a strut between the truss and longitudinal members, substantially as described.

11. In a car of the class described, a combined end sill and body-bolster formed of metal plates vertically disposed and extending longitudinally thereof, angle-irons secured to the upper and lower edges of the same with their flanges extending outwardly therefrom and from the center in a horizontal plane, the longitudinal vertically-disposed members being separate at their transverse center and their flat vertical portions being bent toward each other and secured together at their ends, substantially as described.

12. In a car of the class described, two side plate-girders, one on each side, for supporting the body of the car longitudinally, each girder having a single plate-body and an independent flanged rail on each side at the bottom forming a self-sustained side girder, substantially as described.

13. In a car-body-supporting frame, the combination of a side girder for each side formed of an outer girder having a metal plate-body and separate flanged metal rails united to the metal plate-body at the top and bottom edges thereof and an intermediate stay-girder having a metal plate-body and separate flanged metal rails united to the bottom edges thereof, and a cross-support at each end forming an end sill and body-bolster consisting of a metal plate-body and separate flanged metal rails united to the metal plate-body at the top and bottom edges on the outer face thereof, substantially as described.

14. In a car of the class described, the combination of a portion acting as an end sill and body-bolster, consisting of a cross-support formed by metal plates and independent top and bottom flanged rails on the outer face of the plates and located transversely of the car at each end, two side plate-girders, each consisting of a single metal plate-body, a flanged independent rail on each side of the metal plate-body at the bottom and a flanged independent metal rail on the outer face of the plate-body at the top, each girder supported at its ends only by the combined end sills and body-bolsters, and a hopper-shaped car-body carried by the side girders, substantially as described.

15. In a car of the class described, the combination of a combined end sill and body-bolster consisting of a cross-support formed of metal plates, each plate having at the top and bottom on its outer face an independent flanged rail riveted thereto and located transversely of the car at or near each end, a hopper-shaped car-body having its sides and ends inclined, two side plate-girders supported at their ends by the combined end sills and body-bolsters, each girder consisting of a single metal plate-body, an independent flanged rail at the bottom of the plate-body on each side and riveted thereto, an independent flanged rail at the top of the plate-body and

riveted thereto forming a self-sustained plate-girder on each side of the car supporting the hopper-shaped car-body, and intermediate stay-girders, each consisting of a single metal plate-body and an independent flanged rail on each side at the bottom riveted to the plate-body, supported at the ends by end sills and body-bolsters, and furnishing a support for the hopper-shaped car-body against outward sagging or bending, substantially as described.

16. In a car of the class described, the combination of a combined end sill and body-bolster arranged transversely of and at or near each end of the car and consisting of metal plates, each plate having at the top and bottom on the outer face an independent flanged metal rail riveted thereto, a hopper-shaped car-body having inward-sloping sides and ends and two box-girders supported at their ends upon the combined end sills and body-bolsters and formed of two side plate-girders and two intermediate plate-girders, each side plate-girder consisting of a single metal body and an independent flanged metal rail on each side at the bottom and an independent flanged metal rail at the top of the plate-body and riveted thereto, and each stay-girder consisting of a single metal plate-body and an independent flanged metal rail on each side of the metal plate-body at the bottom and riveted thereto, and means for securing the side plate-girder and its companion stay-girder one to the other at the bottom for the box-girders to support the hopper floor or bottom, substantially as described.

17. In a car of the class described, the combination of a car-body, two side plate-girders supporting the car-body, each consisting of a single metal plate-body and an independent flanged metal rail at the bottom of the metal plate-body on each side and riveted thereto and an independent flanged metal rail at the top of the metal plate-body on the outer face and riveted thereto, and a combined end sill and body-bolster arranged transversely of and secured to the ends of the side plate-girders for supporting the girders and transmitting buffing strain thereto, substantially as described.

18. In a car of the class described, the combination of a car-body, two side plate-girders supporting the car-body, each consisting of a single metal plate-body and an independent flanged metal rail at the bottom of the metal plate-body on each side and riveted thereto and an independent flanged metal rail at the top of the metal body on the outer face thereof and riveted thereto, a combined end sill and body-bolster arranged transversely of and secured to the ends of the side plate-girders and furnishing a support for the girders and transmitting buffing strains thereto, and a draft-bumper at each end of the car projecting from the combined end sill and bolster-body and assisting the combined sill and bolster in carrying the load, substantially as described.

19. In a car of the class described, the combination of a car-body, two side plate-girders supporting the body, each consisting of a single metal plate-body and independent flanged metal rails at the top and bottom of the plate-body and riveted thereto for each girder to have a rail at its top and a rail on each side at the bottom to be self-sustained and support the weight of the body and load, a combined end sill and body-bolster arranged transversely of and secured to the ends of the side plate-girders supporting the girders at the ends and transmitting buffing strains to the girders, a draft-bumper at each end of the car projecting endwise from the combined end sill and bolster, and means for assisting such draft-bumper in resisting sidewise and vertical strains, substantially as described.

20. In a metal car, the combination with side plate-girders, of body-bolsters to which the side girders are secured, a car-body rigidly held between the side girders, reinforcing-standards secured to the side girders and upper edge of the body, and independent connecting-braces between the bolster and body and the side plate-girders and body, substantially as described.

21. The combination with side plate-girders, of end sills rigidly connecting the ends of the girders, a body supported between the girders and braces extending from the upper and lower portions of the end sills to the end of the body, substantially as described.

22. The combination with a side supporting-plate, of an obliquely-arranged hopper-plate riveted thereto at a point above the lower edge of the side plate, and a bracing member inside of said side supporting-plate and having a portion adapted to brace the hopper-plate, substantially as described.

23. The combination with a side supporting-plate, of an obliquely-arranged hopper-plate riveted thereto at a point above the lower edge of the side plate, and a bracing member inside of said side supporting-plate and having a portion adapted to brace the hopper-plate, an angle-bar secured to the lower edge of the side plate, and vertical posts secured to the side plate, substantially as described.

24. The combination with side girders, of an end sill, corner-posts supported directly by said end sill and secured to said side girders, and a car-body whose sides are supported by said side girders and whose ends are supported by said corner-posts, substantially as described.

25. The combination with a metal car-body, of side girders, an end sill connected directly to said side girders, angle corner-posts secured to said girders and supported by said end sill, and whose upper ends are connected to said car-body, substantially as described.

26. In a car of the class described the combination with a body, of a bolster or end sill, draft-rigging members and the plates I³ and

I³ extending from the said members to the body.

27. In a car of the class described, the combination with a body, of a bolster, a draft-rigging member, the brace-plates, I², I³, and the horizontal plates i⁴, i⁵.

28. The combination with a car-body having an overhanging end, of a transverse bolster, corner-posts connected to said bolster and to said overhanging end, a structure supported by said bolster and extending forwardly, and braces for the central portion of said inclined end supported by said forwardly-extending structure and connected to the overhanging end of the car-body, substantially as described.

29. In a car, the combination with side plate-girders, and body-bolsters supporting said plate-girders, of an inclined bottom and supports for said inclined bottom springing from and rigidly secured to said bolster, substantially as described.

30. In a car of the class described, the combination of a combined end sill and body-bolster arranged transversely of and at or near each end of the car, a hopper portion, and side plate-girders supported by said combined end sills and bolsters at each side of the hopper portion and connected to form in effect box-girders, said hopper portion being supported by said side plate-girders, substantially as described.

31. In a hopper-bottom car, a draft-beam extending forwardly from the bolster, the outer end of the draft-beam depending on the overhanging part of the car-body for its vertical support, substantially as described.

32. In a hopper-bottom car, a body-bolster composed of an upper and a lower part, the lower part being bellied down, and also being riveted to the end of the draw-beam, substantially as described.

33. In a car, the combination with a car-body having an overhanging front part, of a bolster, a draft member extending forward from said bolster, and a connection from said draft member to the overhanging part of said car-body for supporting said draft member, substantially as described.

34. In a metal car, the combination with a car-body, of side box-girders extending longitudinally and comprising in their construction plate-girders, a portion of the walls of the car-body, and transverse connections, substantially as described.

35. In a metal car, the combination with a car-body, of side box-girders extending longitudinally and each comprising in its structure a plurality of plate-girders, a portion of the walls of the car-body, and transverse connections, substantially as described.

36. In a car of the class described the combination with the body, of supporting means therefor, a sill or bolster, a cross-piece such as i³ on the body and a brace between the cross-piece and the bolster.

37. In a hopper-bottom car, a draw-beam extending outward from the bolster the outer portion of the draw-beam depending on an overhanging part of the car-body for its vertical support.

38. In a hopper-bottom car a draw-beam extending forward from the bolster and a connection between the draw-beam and an over-

hanging portion of the car-body whereby the draw-beam is supported in its position by the 10 said overhanging portion of the car-body.

HARRY STILLSON HART.
